AUTOMOBILE VISOR ATTACHMENT FOR HOLDING ARTICLES

Herbert S. Chase, Woodmere, N. Y., assignor to Bernard Cahn Co., Inc., New York, N. Y.

Application February 8, 1957, Serial No. 44,808

Term of patent 7 years

(Cl. D14—6)

Fig. 1.

Fig. 2.

Fig. 3.

Figure 1 is a front elevational view of an automobile visor attachment for holding articles showing my new design.

Figure 2 is a side elevational view, and

Figure 3 is a rear elevational view thereof.

I claim:

The ornamental design for an automobile visor attachment for holding articles, substantially as shown.
